HYDRAULIC CYLINDER FOR AGRICULTURAL IMPLEMENT OR THE LIKE

Richard Prince, 405 Water St., Sioux City, Iowa

Filed Apr. 4, 1960, Ser. No. 60,007

Term of patent 14 years

(Cl. D40—1)

FIG. 1 is a top perspective view of a hydraulic cylinder for agriculture implements or the like showing my new design;

FIG. 2 is a rear elevation thereof as seen from the right of FIG. 1;

FIG. 3 is a front elevation thereof as seen from the left of FIG. 1;

FIG. 4 is a top plan view thereof;

FIG. 5 is a side elevation thereof; and

FIG. 6 is a fragmentary bottom plan view thereof.

I claim:

The ornamental design for a hydraulic cylinder for agricultural implements or the like, substantially as shown.
